UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,957, dated July 1, 1890.

Application filed April 15, 1890. Serial No. 348,111. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body portion, which extends upwardly into the flattened crook B, whose free end is curved into a more or less sharp hook. The lower part of the body is formed with an annular band C of plain surface, having upwardly-extending ornamentation of spreading ribs G and similar downwardly-extending 20 ornamentation D. The portion of the body below D, as at E, is shaded to make the parts D stand in high relief, and is mounted at the extreme bottom by an annular band F.

The ornamentation immediately above C and G is extended at H toward the middle of the 25 crook, so as to form a slight horn to make the opening in the crook more pronounced. The upper edge of the crook is plain, as at I, and this part I is separated from the inner or lower portion of the crook, which is also 30 plain, by the ornamental portion J, which ornamentation may be of any suitable configuration.

The handle is made of any suitable material. 35

Having now described my new design, what I claim as new, and desire to secure by Letters Patent, is—

The design for cane or umbrella handles, substantially as herein described and shown. 40

In testimony of which invention I have hereunto set my hand.

HENRY O. SCHMIDT.
